STRIP FEEDING APPARATUS

John T. Davidson and John H. Kroemer, Dayton,
Ohio, assignors to The Standard Register Com-
pany, Dayton, Ohio, a corporation of Ohio

Application May 22, 1947, Serial No. 749,640

9 Claims. (Cl. 271—2.4)

1

This invention pertains to strip feeding and imprinting apparatus, and more particularly to differential feeding mechanism for advancing superposed record strips simultaneously through step by step movements of different extent while progressively reversing one of the strips by turning its under side uppermost, and momentarily arresting both strips with prescribed areas thereof in registry at an imprinting position.

For illustrative purposes, but with no intent to unduly limit the scope or application of the invention, it is herein shown and described in association with a conventional cash register mechanism which embodies imprinting and accumulating devices controlled by a series of manually depressible keys. The present strip feeding apparatus in association with such register mechanism may be employed for check writing or listing purposes.

One of the present record strips comprises a continuous succession of series connected detachable printed forms such as checks, vouchers, utility bills, invoices, statements or analogous record sheets, advanced one form length at a time past an imprinting position, where the succeeding forms receive entries of sums or amounts and other data determined by operation of the register control keys. The other record strip is concurrently advanced through line by line spaces and simultaneously receives duplicate imprints. This detail or data strip may also be separable at longitudinally spaced intervals upon transverse division lines into individual sheets which may be subsequently collected into book form. In such event the duplicate imprints thereon are arranged in separate groups, preceded by skip spaces of greater extent than line spaces to accommodate headings for the separable sheets or pages.

The total of succeeding amounts imprinted upon the record forms and duplicated on the detail or data strip is progressively accumulated upon the totalizers of the register mechanism.

The detail or data strip receiving the duplicate record imprints may have been previously inscribed with a succession of names, numbers, or other identifying indicia pertaining to the checks, bills or statements comprising the companion record strip, in association with which the duplicate imprints are to be effected. The register mechanism is ordinarily designed to print downwardly upon the upturned face of the main record strip of series connected detachable printed forms, and upwardly upon the under side of the duplicate record strip. The latter

2

is preferably inserted in the register mechanism in relation with the printing devices thereof in an inverted position, with its inscribed face downwardly to receive the successive duplicate imprints. However, means is provided for progressively reversing a longitudinal portion of the detail or data record strip as it is advanced past the imprinting position whereby one marginal portion thereof bearing the names, numbers or identifying indicia will be overturned and rendered visible through an observation opening, while the opposite marginal portion of the strip remains in downturned position to receive the duplicate imprints.

15 The particular cash register mechanism illustrated in association with the present strip feeding apparatus is of conventional form, and forms no part, per se, of the present invention, other than affording a convenient imprinting and 20 totalizing apparatus for conjoint use with the present strip feeding apparatus.

In lieu of the cash register mechanism shown, the present invention may be associated with other writing or recording apparatus, check 25 writer, addressing machine or tabulator operable upon continuous strip stationery.

The object of the invention is to improve the construction as well as the means and mode of 30 operation of strip feeding and imprinting apparatus, whereby it may not only be economically manufactured, but will be more efficient in use, automatic in operation, uniform in action, having relatively few operating parts, and be unlikely to get out of repair.

35 A further object of the invention is to provide recording and listing mechanism simultaneously operative upon differentially advanced record strips, and means for accurately presenting differently spaced record receiving areas thereof simultaneously in registry at the imprinting position.

A further object of the invention is to provide strip reversing means for progressively turning the strip upside down in unison with its advancement.

45 A further object of the invention is to provide a strip feeding and imprinting mechanism possessing the advantageous structural features, the inherent meritorious characteristics and the mode of operation herein set forth, or their equivalents.

With the above primary and other incidental objects in view as will more fully appear in the specification, the invention intended to be protected by Letters Patent consists of the features

of construction, the parts and combinations thereof, and the mode of operation, as herein-after described or illustrated in the accompanying drawings, or their equivalents.

In the accompanying drawing, wherein is illustrated the preferred, but obviously not necessarily the only form of embodiment of the invention,

Fig. 1 is a perspective view of a strip feeding and imprinting apparatus embodying the present invention, associated with a conventional cooperating cash register mechanism.

Fig. 2 is an elevational view of the strip feeding mechanism for progressively advancing the main record strip of series connected detachable form stationery.

Fig. 3 is a similar view of the strip feeding mechanism for progressively advancing the duplicate record or list strip for effecting its reversal.

Fig. 4 is a detail view of the detail or listing strip advancing means on line 4—4 of Fig. 3.

Fig. 5 is a detail view of a one revolution clutch employed in both the main record strip and listing strip feeding mechanism on line 5—5 of Fig. 3.

Fig. 6 is a detail sectional elevational view, from the right, on line 6—6 of Fig. 3.

Fig. 7 is a detail view from the extreme right, on line 7—7 of Fig. 3.

Like parts are indicated by similar characters of reference throughout the several views.

The present embodiment of the invention comprises an attachment or supplemental mechanism, which as shown in Fig. 1 is mounted upon a conventional cash register 1. The supplemental mechanism is actuated independently of the cash register driving means for differentially advancing record strips 2 and 3 past imprinting devices enclosed in a box-like housing 4. The imprinting devices within the housing 4 are actuated by operation of the cash register machine under control of manually depressible keys on the front of the cash register 1. The imprinting devices, which are a part of the cash register 1, operate downwardly to impress indicia upon the previously positioned form or section of the record strip 2. The imprinting devices are simultaneously operated in an upwardly direction to impress like indicia upon the under side of the record strip 3. Such imprinting devices are component parts of the cash register 1.

Both strips 2 and 3 are fed simultaneously in opposite directions past the imprinting position. Strip 2 is fed from right to left past the imprinting position, while the upper tally or detail strip 3 is advanced from left to right past the imprinting position. Although being advanced simultaneously, the respective strips 2 and 3 are advanced different distances during each feeding operation.

The record strip 2 which comprises a continuous series of connected succession of detachable checks, utility bills, invoices, or analogous forms, faces upwardly over a strip guide 5 and thence beneath the printing device housing 4. The strip 2 is advanced independently of the detail strip 3, but in unison therewith by feeding mechanism contained within a housing 6 dependent beneath the strip guide 5, at the left of Fig. 1.

Form strip feeding unit

The form length feeding unit for advancing the record strip 2, illustrated in Fig. 2, is actuated by an electric motor 7. The circuit for the motor 7 is controlled by a manual switch 8 on the side of the housing 6. The motor continues to operate until the switch 8 is reversed. A signal light 9

in the motor circuit indicates that the motor is in operation. The motor 7, acting through a reduction gear train within the housing 7a drives a gear pinion 10 meshing with a pinion 11 fast upon a shaft 12. The shaft 12 carries a drive pulley 13. Adjacent the gear pinion 11 the shaft 12 carries a small ratchet wheel 14. Contiguous thereto is a loose sleeve 15 having at one end thereof a gear pinion 16. Adjacent to the ratchet wheel, the sleeve 15 carries a disc 17 supporting a spring actuated pawl 18 engageable when released with the ratchet wheel 14. The pivoted pawl 18 is provided with an arm 19 projecting beyond the periphery of the disc 17 and engageable at the limit of rotation of the disc, with the extremity of an oscillatory lever 20, to automatically disengage the pawl from the ratchet wheel 14. The sleeve 15 and disc 17 carrying the pawl 18, engageable with the ratchet wheel 14, forms a one revolution driving clutch, intermittently connecting the sleeve 15 and gear pinion 16 with the shaft 12. At completion of each rotation of the sleeve 15 and disc 17 with the shaft, the protruding end of the arm 19 of the pawl 18 engages the end of the upstanding lever 20 to oscillate the pawl 18, against the tension of its retracting spring 22, out of engagement with the ratchet wheel 14, thus arresting the rotation of the sleeve 15 and gear 16. The gear 16 meshes with a driven gear 23 upon a transverse pin wheel shaft 24, which carries two concentric axially spaced pin wheels 25. The pin wheels 25 are loosely mounted on the shaft 24 and are interconnected for unison rotation by an intermediate coupling sleeve 26 having interlocking clutch engagement 27 at each end with the respective pin wheels. The interconnected pin wheels are adjustably connected to the shaft 24 for unison rotation by a conventional variable coupling 28, such as commonly employed upon typewriters.

The purpose of the variable coupling 28 is to enable the forms comprising the record strip 2 to be initially correctly located relative to the point of engagement of the printing devices. After adjustment the variable coupling is locked to positively interengage the pin wheels 25 and shaft 24 for unison rotation. The pin wheels 25 progressively engage in longitudinally spaced marginally punched feed holes 29 in the record strip 2. The pin wheels 25 engage with the record strip 2 coincident with a pair of slotted paper guide fingers 30 of which only one appears in Fig. 1. The intermeshing gears 16 and 23 are so proportioned that one complete rotation of the gear 16 incident to engagement of the pawl 18 with the ratchet wheel 14 and its subsequent release by engagement of the trip arm 19 with the end of the movable lever 20, will rotate the pin wheels sufficiently to advance the strip 2 the distance of one form, check, bill or invoice.

The recording operation is initiated by depression of one or more of the cash register value keys which are effective to set up a sum in dollars and cents and perhaps some accompanying indicia, to be printed upon the strip, check, bill or invoice, and sets the mechanism to accumulate the sum upon the register totalizer upon subsequent operation of the register mechanism. The actual imprinting operation is then effected by actuation of one of the operation determining keys which effects operation of the imprinting devices within the housing 4 to imprint the amount at a predetermined position on the advanced form, check or bill, and also on the detail strip 3. It also effects simultaneously accumu-

lation of such amounts upon the register totalizer. These are the normal intended functions of the cash register mechanism. In addition thereto the cash register key is especially adapted when depressed to close through the cash register mechanism an electric circuit 1c which energizes a solenoid 31, the reciprocatory core of which is connected with the lower end of the oscillatory stop lever 20 pivoted at 33 to retract the lower end of the lever 20 against the resistance of its spring 34. By such movement the upper end of the lever 20 is withdrawn from beneath the protruding arm 19 of the spring pawl 18 to enable its engagement with the ratchet wheel 14 for one complete rotation of the shaft 12, gear 16 and disc 17 carried thereby. At the limit of such rotation the pawl is again automatically disengaged by contact with the end of the pawl arm 19 with the stop lever 20. Thereupon the advancement of the record strip 2 ceases until a cash register key 1b is again depressed.

Detail strip feeding unit

The superposed data strip 3 is advanced in unison with the advancement to the strip 2 of forms, but through much shorter distances. The strip 3 is advanced through successive line spaces whereas the strip 2 is advanced a form length at each operation. The lengths of the forms may vary and the feeding means must be correspondingly changed, by interchange of gear elements of different sizes.

The detail or data strip 3 is advanced over the strip guide 34, at the left of Fig. 1, face side downwardly. The detail or data strip 3 has been previously passed through an addressing machine, a typewriter or other imprinting apparatus by which a series of names to whom the forms, checks, bills or other records comprising the strip 2 pertain, or the list bears a succession of identifying indicia in association with which an amount agreeing with that imprinted on the corresponding form of strip 2 is to be imprinted. As before stated the cash register imprinting devices are such that while the imprinting of the forms of strip 2 is effected downwardly on the upturned face of strip 2, other printing devices of the cash register are operative upwardly against the downturned portion of the face of the detail or data strip 3. Such oppositely directed imprint operation is a peculiarity of the instant cash register mechanism. Other embodiments of printing devices may be substituted therefor.

It is desirable however that the operator be able to definitely ascertain the name of the particular person whose form, check, bill or the like is being concurrently imprinted. The previously imposed identification imprints, being on the under side of the record strip 3 as it is advanced from its source of supply, at the left of Fig. 1, the record strip 3 is partially folded over in a diagonal form, enabling the identification imprints to become visible upon the overturned portion, and the record strip is progressively advanced in such position. In overfolding the margin of the strip bearing the identification imprints, it is turned over a guide block 35, which also serves as a platen for the upwardly directed imprinting devices against the portion of the record strip extending over the housing 4 and beneath the platen block 35. By continuing the advancement of the strip 3 with the overturned margin fed progressively diagonally, and while the opposite or under margin is fed in a straight

path the strip is eventually entirely overturned face upwardly.

The detail or data strip feeding mechanism is illustrated in Fig. 3. The feeding unit is driven by a belt 36, from the pulley 13 of the form strip feeding unit, Fig. 2. The drive belt 36 engages a pulley 37 upon a shaft 38. Loosely mounted on the shaft 38 is a sleeve 39 which carries a gear pinion 40 having a segment of increased thickness or width of face 41 and in spaced axial alignment therewith a cam 42. The sleeve 39 with the gear 40 and cam 42 are detachably engageable with the shaft 38 by a single revolution clutch mechanism of the same construction before described, which is illustrated in Fig. 5. That is to say, the shaft 38 carries fast to it a ratchet wheel 14. Adjacent to the ratchet wheel 14 a disc 17 is attached to the sleeve 39. To the disc 17 is pivoted a spring actuated pawl 18 engageable with the ratchet wheel 14. The engagement of the pawl 18 is effective to temporarily connect the sleeve 39 together with the gear pinion 40 and cam 42 for unison rotation with the shaft 38. An arm 19 integral with the pawl 18 protrudes beyond the periphery of the disc 17. At the completion of each rotation of the sleeve 39 and gear 40 and cam 42, in unison with the shaft 38, the arm 19 engages with the extremity of an oscillatory lever 43, which corresponds to the lever 20 of the form strip feeding unit, Fig. 2. Engagement of the arm 19 with the lever 43 automatically disengages the pawl 18 from the ratchet wheel 14 against the tension of its retracting spring 22. To initiate the advance of the detail or data strip 3, the lever 43 is automatically withdrawn by energization of a solenoid 44 to retract the lower end of the lever 43 against the yielding resistance of its spring 45. An electrical circuit is closed to energize the solenoid to initiate the feeding operation by manipulation of one or another of the keys 1b of the cash register, after the predetermined amount or indicia to be imprinted has been set up. The cash register is thereby operated to imprint the selected amount and accumulate the same on the totalizer of the machine. The register key for energizing the solenoid 44 to cause advancement of the detail record strip is the same key 1b operated to effect the imprinting and advancement of the form strip 2 as previously described. In fact the initiation of operation of both strip feeding units occurs simultaneously as a single operation. The imprints upon the detail or data strip 3 are effected in successive groups at line space intervals with a wider heading space skip between.

The gear pinion 40 upon the revolute sleeve 39 having the laterally extended integral gear segment 41 meshes with a gear wheel 46 also having a laterally extended integral gear segment 47. The peripheral face of the latter is equal to the extent of the entire peripheral face of the gear pinion 40. The gear 46 is the initial member of a gear train intermittently driving the strip feeding devices to advance the strip through step by step line spacing movements, including one step of longer duration to compensate for the heading space of each group of line spacers.

Such increased advancement compensates for the form heading. The continuous face of the gear pinion 40 is positioned in laterally offset relation with the main continuous face of the gear 46. The lateral extension 47 of the gear 46 is equal to the peripheral extent of the gear pinion 40. Thus at each actuation of the sleeve 39 and gear pinion 40 while the latter is in mesh with

the gear extension 41, the gear 46 is driven throughout the full rotation of the pinion 40 to actuate the strip feeding devices through the longer step. During other rotations of the gear pinion wherein the lateral extension 41 of the gear pinion is in mesh with the main peripheral face of the driven gear 46, the latter gear is advanced through only short steps corresponding to line space advancements of the feeding devices, and the main continuous body of the gear pinion travels idly past the gear 46 in a laterally offset path.

Connected with the gear 46 and revoluble in unison therewith is a peripherally notched disc 48, the uniformly spaced notches 49 of which agree with the successive line spacing of the feeding device, and one longer intermediate space 50 corresponds to the heading space skip, before mentioned.

Successively engageable with the notches 49 of the disc 48 is an oscillatory locking pawl or detent arm 51, which is raised by the rotary cam 42 at each rotation of the sleeve 39 to lock the mechanism at the end of each advancing movement of the feeding mechanism and holds it stationary during the imprinting operation.

Connected to the gear 46 at its side opposite the notched disc 48 for unison rotation is a gear wheel 52 which drives through idler pinions 53 and 54, a gear pinion 55 on a pin wheel shaft 56. The shaft 56 loosely carries two axially spaced pin wheels 57 and 58 which are intercoupled with each other and with a further gear pinion 59 by intermediate coupling sleeves 60 and 61. The pin wheels 57 and 58 and coupling sleeves 60 and 61 and the gear pinion 59 are adjustably engageable with the pin wheel drive shaft 56 by a conventional variable coupling 62 which is accessible at the front of the apparatus. By this means the pin wheels may be revolubly adjusted to and fro relative to the driving mechanism to register particular areas of the record strip with the imprinting devices.

The pin wheels 57 and 58 are engageable in marginally punched holes in opposite margins of a supplemental record strip (not shown) to progressively advance the strip in the usual manner without reversal. Such supplemental record strip is necessary for the recording of certain types of business transactions, hence means are provided for the advancement of such supplemental strip in synchronism with the advancement of strips 2 and 3.

However, to advance the record strip 3 with one margin overturned an askew pin wheel 63 engages the overturned punched margin, as is illustrated in Fig. 4, while the pin wheel 57 engages the other punched margin thereof.

The askew pin wheel 63 is mounted on a diagonal shaft 64, having therein a universal joint 65. The gear pinion 59 upon the revoluble coupling sleeve 61 drives through an idler pinion 66, a gear pinion 67 on the universally jointed shaft 64 to drive the askew pin wheel in unison with the pin wheel 57. The askew pin wheel 63 is revolubly adjustable by means of the variable 62, in unison with the pin wheels 57 and 58.

Mounted on the universal shaft 64 and meshing with the pin wheel shaft drive pinion 55, is a toothed counter wheel 68 bearing indicia identifying the line spaces as they are advanced to and past the imprinting position.

The detail or data strip feeding mechanism, illustrated in Fig. 3 is mounted beneath the continuing record strip guide at the right of Fig. 1

with the driving mechanism in dependent position there behind. The positions of the pin wheel 58 and askew pin wheel 63 and the variable coupling 62 on the extremity of the pin wheel shaft 56 are visible at the right of Fig. 1. Closely beside the variable coupling 62, Figs. 1 and 7, is shown a push button 69, in the electrical control circuit of the solenoid 44 in multiple with the operation determining key of the cash register or recording mechanism. By depression of the button 69 the detail strip feeding mechanism may be actuated independently of the operation of the cash register or other recording mechanism to advance the detail or data strip 3 into synchronism with the series connected strip of forms 2, whereby corresponding areas may be positioned in printing position in starting operations.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific features shown, but that the means and construction herein disclosed comprise the preferred form of several modes of putting the invention into effect, and the invention is therefore claimed in any of its forms or modifications within the legitimate and valid scope of the appended claims.

Having thus described our invention, we claim:

1. Strip feeding apparatus whereby a plurality of superposed record strips are differentially advanced past a recording position while progressively overturning one of the strips simultaneously with their advancement, including separate feeding mechanisms for different strips of the plurality, common actuating means therefor, guide means relative to which one of the superposed record strips is turned with one margin thereof in divergently overlapping relation with the opposite margin of the same strip, one of said strip feeding mechanisms being operative to simultaneously advance the opposite divergent margins of said one strip in longitudinal paths at equal rates of speed.

2. Means for reversing a strip of material by turning its under side uppermost simultaneously with its advancement, including guiding means relative to which the strip is advanced, guiding one longitudinal margin thereof into angularly divergent overlapping relation with the opposite longitudinal margin of the strip, and feeding means separately engageable with the margins of the strip for simultaneously longitudinally advancing the divergently overlapping margins of the strip at the same rate of travel.

3. Strip feeding apparatus for differentially advancing a plurality of record strips past an imprinting position while progressively reversing one of the plurality of strips, including a strip feeding apparatus progressively advancing one of the strips through a succession of relatively short step by step advancements, another strip feeding apparatus progressively advancing a different one of the plurality of strips through step by step movements of greater extent in synchronism with the shorter step by step advancement

of first mentioned one of the plurality of strips, energizing means therefor simultaneously actuating the strip feeding apparatus, and guiding means relative to which one of the strips is advanced by which said one strip is turned upon itself with one longitudinal margin thereof divergently extending in overlapping relation with the opposite longitudinal margin thereof and simultaneously advanced at equal rate of travel by the corresponding strip feeding apparatus.

4. A strip feeding apparatus, wherein plural superposed continuous strips are differentially advanced simultaneously relative to a recording mechanism by which different strips of the plurality are impressed in opposite directions, the upper strips being impressed on their under side and the lower strip simultaneously impressed upon their upper side, characterized by a differential strip feeding mechanism advancing different strips different distances in unison and arresting the different strips with differently spaced areas thereof in registry at the recording position, and reversing means automatically overturning the strips impressed upon their under side to present their impressed side uppermost, simultaneously with their advancement.

5. A strip feeding apparatus for differentially advancing a plurality of superposed record strips past imprinting devices while progressively reversing one of the plurality of strips characterized by a guide directing a marginal area of said one of the plurality of strips in a direction angularly inclined to the opposite marginal area of the same strip, and a pair of strip feeding elements operable in divergently disposed planes respectively engaging the opposite angularly inclined marginal areas of the same strip simultaneously advancing the opposite marginal areas thereof at equal rates of speed.

6. A strip feeding apparatus wherein superposed record strips are differentially advanced relative to a recording apparatus characterized by separate strip feeding devices one of which advances certain of the strips through succeeding line spaces and the other of which simultaneously advances other of the plurality of strips through succeeding form length distances, common actuating means for the strip feeding devices, and reversing means for progressively overturning certain of the plurality of strips about their longitudinal axes simultaneously with the advancement thereof.

7. A strip feeding apparatus wherein plural record strips are differentially advanced relative to recording means operative in opposite directions upon different strips of the plurality thereof, characterized by a strip feeding mechanism for advancing certain of the plurality of strips through step by step movements of lesser extent and strip feeding mechanism for ad-

vancing certain other of the plurality of strips through step by step movements of greater extent in unison with the step by step movements of lesser extent of the first mentioned part of the strips, actuating means therefor common to the plurality of strip feeding mechanisms and reversing means for overturning at least certain of the strips about their longitudinal axes in unison with advancement thereof.

10 8. A strip feeding apparatus wherein superposed record strips are progressively advanced past an imprinting position for simultaneous imprinting upon the top face of one strip and the under face of the other strip, characterized by strip feeding apparatus for progressively advancing one of the strips predetermined distances of greater extent, and the other strip predetermined lesser distances and arresting both strips in registering relation coincident with the imprinting position, and strip reversing means including a portion of the strip feeding apparatus capable of progressively turning the strip printed on its under face by presenting its under face uppermost simultaneously with its advancement.

15 9. Strip feeding apparatus including a pair of strip feeding devices operable in overlapping divergent planes and engageable with opposite margins of the same strip of material, one margin of the strip being engaged by one of said strip feeding devices and the other margin of the strip being engaged by the other of said strip feeding devices, motion transmitting means for actuating the said strip feeding devices in unison at the same rate of speed, and a guide 20 block about which the strip turns in response to actuation of said strip feeding devices, the construction and arrangement being such that the strip of material is reversed with its bottom side turned uppermost simultaneously with its advancement.
